UNITED STATES PATENT OFFICE.

MILLARD F. FIELD, OF BOSTON, MASSACHUSETTS.

DETECTOR-RELIEF DEVICE.

1,115,798.

Specification of Letters Patent.

Patented Nov. 3, 1914.

Application filed December 21, 1906. Serial No. 348,694.

To all whom it may concern:

Be it known that I, MILLARD F. FIELD, a citizen of the United States, residing at Boston, in the county of Suffolk and State 5 of Massachusetts, have invented an Improvement in Detector-Relief Devices, of which the following description, in connection with the accompanying drawings, is a specification, like letters on the drawings 10 representing like parts.

My invention provides an automatic stop motion for looms, in which all injurious pressure on the warp detector (which term I use to include any equivalent detecting 15 device) is done away with and is replaced by a delicate relief mechanism which relieves the detector of all strain, so that an extremely light, delicate detector may be employed.

As now commonly employed, the detector drops between a comb movably carried by the detector-supporting frame and an arm of the vibrator, so that the entire force of the vibrator is brought against the frail 20 detector, which is obliged to withstand this heavy pressure every time the loom is automatically stopped. The result is that certain kinds of detectors cannot be used, as for instance an open detector is so slender and 25 light that it would be bent and injured by the heavy pressure of the vibrator against the same in order that the vibrator should be stopped by the dropping of the detector. It is often desirable however to employ 30 light, open detectors. By my invention any kind of detector may be employed, as my invention protects the detector from all injurious pressure and injury. To this end I provide an auxiliary relief device, so constructed and positioned that it is set by the dropping or setting movement of the detector, and when set it coöperates with the shipper actuating mechanism to move the shipper to loom-stopping position. This relief device preferably cooperates with the vibrator of the loom, and in the following drawings I have shown several embodiments thereof, in each of which it will be observed 45 that the relief device is so delicately poised and located that it is swung into actuating position by the presence of the detector without offering substantial resistance or bringing any pressure against the detector, the stopping action of the relief device being entirely independent of the detector and de-

pending solely upon the relative position of the relief device and the vibrator or other shipper actuator.

In the drawings, Figures 1 and 2 are views in cross-section and front elevation of 60 a sufficient portion of a loom to enable my invention to be readily understood; and Fig. 3 is a fragmentary view similar to Fig. 1, showing the parts in loom-stopping position.

Adjustably supported on the frame 1 of the loom is a usual detector frame 2, on whose transverse wires or detector guides 3 any desired kind of detectors 4 are mounted to coöperate with the warps 6 passing over 70 usual lease rods 7, all in usual manner. The detector frame is held together and rendered rigid by usual frame sides 8 and brace bar 9 and rod 10, which however do not constitute any essential part of my invention. 75 Pivotedly mounted in convenient position for coöperating with the detectors 4 are opposite relief mechanisms, herein shown as comprising bars or transverse rails or plates 11 suspended by wings 12 rigidly from 80 rocker shafts 13 to the outer ends of which are fixed depending hooks 14 preferably made adjustable by suitable means, as a slot 15 in a plate 16 and a set screw 17 in an arm 18. The opposite arms 18 of the opposite relief devices are normally held toward each other by a spring 19, suitable stops 20 being provided to limit their inward movement. The actuating bars or rails 11 extend across the loom in position to be engaged 85 by the lower ends of the detectors whenever the latter drop to stop the loom, and are approximately on a level with a vibrating tip 21 of the vibrator 22, which is supported by arms 23 from a usual vibrator rod or 90 shaft 24 connected by usual or preferred means with the shipper arm or stopping device of the loom. As these latter parts are common and well-known, I have omitted showing the same herein. The vibrator 95 may be connected to the shipper rod in any well known manner, for example, as shown in the patent to Allen, 640,154, Dec. 26, 1899, or the patent to E. S. Stimpson, 673,824, dated May 7, 1901. Adjacent the 100 catches or hooks 14 I provide oppositely extending arms 25 projecting rigidly from the vibrator rod or shaft 24 and carrying at their free ends stop pins 26 in position to be 105 engaged by one or the other of the hooks 14 110

of the relief devices when the latter are moved from inoperative position Fig. 1 to operative position as shown in Fig. 3.

From the above description it will be readily apparent that as long as the loom is working properly and the detectors therefore remain raised as shown in Fig. 1, the relief devices remain pulled inwardly by the light spring 19, but the moment that a warp thread breaks the corresponding detector instantly falls and as the vibrator 22 swings over, the tip engages the depending detector and instantly pushes it over to the position shown in Fig. 3, thereby rocking the relief device into stopping position so that its hook 14 is in the path of the adjacent stop pin 26 and thereby stops said pin, and through the connecting mechanism stops the loom. It will be observed that the stopping strain or heavy pressure of the vibrator does not come upon the detector but comes directly on the relief device, and the latter yields and affords relief against damage to the delicate detector. The stop pin 26 strikes downwardly on the hook 14 so that the entire stopping strain is transmitted in a straight line to the shaft 13 and is taken up by the rigid and strong detector frame, so that the delicate detector itself is relieved of all rough usage and cannot be injured in the slightest. When the vibrator tip 21 strikes against the detector the latter and the relief device yield forwardly freely without offering any substantial resistance, instead of moving against a fixed rigid comb as heretofore. In other words, the detector does not itself stop the vibrator, but simply moves an intermediary part into position so that the latter can stop the vibrator or can set mechanism into motion which will stop the loom.

I believe that I am the first to devise means for accomplishing the above result, and accordingly I wish it understood that my invention is not restricted to any specific mechanism but may be embodied in a wide variety of mechanisms.

It will be understood that the particular embodiment of the invention will vary according to the kind of loom in which it is to be used, and will depend largely upon the form of shipper mechanism or stopping device with which the loom is provided.

The invention broadly stated resides in providing a loom-stop actuator which is set in operation merely by the warp detector or stop-motion detector, so that the detector itself is not required to itself perform the stopping operation. In other words, I interpose an intermediary stopping device which performs the stopping operation and protects the detector by relieving the latter of the severe strains and usage to which it has previously been subjected. All that the de-

tector is required to do is to place the intermediary in proper position for performing its stopping function. The detector itself receives none of the stopping pressure, whereas previously it received all the stopping pressure.

It will be understood that my invention is in no way dependent upon any particular form of stopping mechanism or connections between the detector and the stopping mechanism, but that the stopping mechanism and connections thereto may be widely varied. All that is necessary in order to carry out my invention is to interpose between the detector and said stopping mechanism or connections means for actuating the stopping mechanism as distinguished from requiring the detector itself to actuate the stopping mechanism.

Having described my invention what I claim as new and desire to secure by Letters Patent is,

1. An automatic stop motion for looms, comprising a warp detector movable into loom-stopping position when said warp breaks, a vibrator arranged to vibrate adjacent said detector, a yielding relief device in position to be actuated by said detector and vibrator, and movable stopping means in the path of said relief device cooperating with the latter to stop the vibrator.

2. An automatic stop motion for looms, comprising a warp detector movable into loom-stopping position when said warp breaks, a movable relief device arranged to engage the detector when in the latter position, a vibrator arranged to engage the detector opposite said relief device and thereby actuate the relief device, and stopping means carried by the vibrator to be engaged by said relief device when the latter is actuated by the vibrator.

3. An automatic stop motion for looms, comprising a warp detector frame, a series of warp detectors mounted therein and arranged to move independently into loom-stopping position when their respective warp breaks, a movable relief device having a transverse bar in position to be engaged by any one of said detectors when in loom-stopping position, a vibrator rod, a transversely extending vibrator operated thereby in the path of said detector when in said loom-stopping position, and means actuated by said relief device for stopping the vibrator when the latter engages the detector which is in loom-stopping position.

4. An automatic stop motion for looms, comprising a warp detector frame, a series of detectors mounted therein and arranged to move independently into loom-stopping position upon the breaking of the given warp, a movable relief device having a transverse bar in position to be moved by any one of said detectors when in loom-stopping

position, a vibrator rod, a transversely extending vibrator operated thereby in the path of said detectors when in said loom-stopping position, and a stopping member 5 extending rigidly from said vibrator rod in position to be stopped by said relief device when the latter is moved into stopping position by the engagement of the vibrator with a detector in loom-stopping position.

In testimony whereof, I have signed my 10 name to this specification, in the presence of two subscribing witnesses.
